[57] CLAIM

The ornamental design for a guitar body, as shown.

DESCRIPTION

FIG. 1 is a top, front and left side perspective view of a guitar body showing my new design;

FIG. 2 is a top rear and left side perspective view thereof;

FIG. 3 is a rear elevational view thereof;

FIG. 4 is a left side elevational view thereof; and

FIG. 5 is a top, rear and right side perspective view thereof.

The broken line showing of the guitar neck and strings is for illustrative purposes only and forms no part of the claimed design.
